(57) **CLAIM**

The ornamental design for a refrigerator, as shown and described.

DESCRIPTION

FIG. 1 is a front elevational view of a refrigerator showing our new design;

FIG. 2 is a rear elevational view thereof;

FIG. 3 is a left side view thereof;

FIG. 4 is a right side view thereof;

FIG. 5 is a top plan view thereof;

FIG. 6 is a first perspective view thereof;

FIG. 7 is a second perspective view thereof;

FIG. 8 is a third perspective view thereof; and,

FIG. 9 is a fourth perspective view thereof.

The broken lines are for illustrative purposes only and form no part of the claimed design.
